CLAIM

The ornamental design of an edging block, as shown and described.

DESCRIPTION

FIG. 1 is a top, side and front perspective view of a block showing my new design, it being understood the opposite side is a mirror image and the back side is a like image thereof;

FIG. 2 is a top plan view of the edging block of FIG. 1; and, FIG. 3 is a partial side elevation view of the edging block of FIGS. 1 and 2.

The surface or portion of the article not shown in the drawing or described in the specification form no part of the claimed design.
